ABSTRACT OF THE DISCLOSURE

An inflatable double track escape chute and method of manufacture involving the steps of forming longitudinal, inflatable tubular members and cross inflatable tubular members which are connected in fluid-tight communication with a flexible sheet secured across them to serve as a slide surface. The longitudinal members are preferably formed in sections connected in tandem with the axes of the sections from top to bottom being progressively disposed at smaller angles with respect to the horizontal, in order to provide a steep initial rapid escape slide which levels out to cushion and brake the fall. An intermediate longitudinal tubular divider separating the two tracks is secured to the flexible sheet in collapsed condition after the tubular members are inflated and the flexible sheet is under a certain amount of tension. Then, when the divider tube is inflated it will further tension the flexible sheet. The divider tube is preferably of a straight axis to provide additional longitudinal tensioning to the flexible sheet.

This invention relates to an inflatable escape slide and more particularly, to an inflatable double slide having a central divider member which provides a two track slide for greater evacuation capacity, and which gives additional tensioning and stiffening of the flexible slide surface.

At the present time there is an increasing trend toward the development of jet passenger aircraft adapted for larger and larger passenger loads. Consequently, there is a growing concern over the ability of present airport facilities to accommodate the rapid loading and unloading of several hundred passengers from a single flight. It is obvious that, in the event of an emergency landing or interruption of take-off wherein it is highly desirable that all personnel aboard leave the aircraft as rapidly as possible, the problems of mass disembarkation are magnified manifold. In order to accommodate such increased demands, there has previously been developed a double inflatable slide which is described in Holcombe U.S. Patent No. 3,370,684 dated Feb. 27, 1968. The double slide there shown comprises three longitudinal tubes of similar configuration, each having a series of sections formed in tandem wherein their axes are at progressively smaller angles with respect to the horizontal and with the junction between sections providing a bendable portion of the beam to cushion the fall of the evacuees. Such slides have worked successfully in that they provide greatly increased accommodation for evacuation but they suffer some disadvantage in that the flexible sheet slide surface is not sufficiently taut to provide as effective a slide as might be desired.

It is, therefore, an object of this invention to provide an inflatable escape slide having vastly increased escape capacity.

It is a further object of this invention to provide an inflatable escape slide with a central divided member to separate slide surfaces for increased evacuation rate.

It is a further object of this invention to provide an inflatable double escape slide wherein the central divider tube has a single continuous axis so that when inflated it

2

tends to assume a straight configuration, and hence provides greater overall rigidity in conjunction with the sectioned longitudinal inflatable beams.

It is a further object of this invention to provide a method of forming a double escape slide wherein the divider tube is secured to the slide surface after the longitudinal beams have been inflated to tension the slide surface sheet between them.

In carrying out this invention, I provide a pair of longitudinal beams which are sectioned in tandem at progressively smaller angles to the horizon when inflated to form a relatively steep slide initially for rapid descent and gradually shallower slide to slow the evacuees at the bottom. The longitudinal beams are connected to two or more transverse beams, including one at the top and at the bottom, with a flexible slide surface sheet bonded across them. Then, the tubular members are all inflated to tension the sheet between them. Thereafter, a longitudinal divider tube is secured to the slide surface sheet while collapsed, preferably by bonding another sheet over the collapsed divider tube and to the slide surface sheet along both edges. Then, the divider tube is brought into fluid communication with one of the longitudinal or transverse inflatable members so that upon subsequent inflation the divider tube will be inflated to further tension the slide surface. Preferably, the divider tube is of single straight axis so that when inflated it will provide further longitudinal strength to the slide surface.

Other objects and advantages of this invention will become apparent from the description following when read in conjunction with the accompanying drawings where:

FIG. 1 is a top slant view of an escape slide embodying features of my invention;

FIG. 2 is a side elevation view of the escape slide;

FIG. 3 is a section view taken along line 3—3 prior to inflation of the central divider tube; and

FIG. 4 is a section view taken along line 3—3 of FIG. 1 after inflation of the central divider tube.

Referring now more particularly to FIGS. 1 and 2, my high-capacity, double escape slide 10 includes a pair of side beams 12, each of which is formed in two or more sections, here shown as sections 12a, 12b, 12c, 12d and 12e which are joined in tandem along junctions 14, with the tandem series of communicating sections being in continuous communication and being disposed at progressively smaller angles with respect to the horizon when the escape slide is inflated and supported between the aircraft A and the ground G. The progressively reduced angles provide for an initial rapid descent at the relatively steep upper sections 12a and 12b and, in addition, the hinge joints 14 constitute yieldable members which further reduce the rate of descent without tending to spring back in a trampoline effect.

Interconnecting the upper ends of the side beams 12 and in inflating communication therewith are upper and lower cross support members 16 and 18 respectively. In addition, intermediate inflatable transverse members 20 are provided to interconnect the beams at one or more locations along the length. These intermediate members may be of relatively small diameter since their primary function is not one of load bearing but merely to maintain the separated parallel relationship of the longitudinal beams 12 and 14 and to resist the rotational forces in these beams when the slide surface is loaded.

Preferably, the beam sections are formed of diameters sufficient to resist maximum anticipated loads where needed, but small enough where possible to minimize inflation volume. For that reason, the sections 12, however many are employed, progressively increase in diameter from their tops where they merge with the cross member 16 to a maximum diameter at the point of maximum beam

loading which may occur at about their mid-points. In the slide shown, this occurs at the second hinge joint 14 where the rate angle of descent is reduced slightly. Through a range of inclination angles, dependent upon the height of the upper anchor panel 22 at the aircraft A, this joint is approximately midway between the beam supports at A and G where bending moments are at a maximum. At subsequent hinge joints 14 the sections extend at progressively slighter angles further to increase the braking effects of friction. Finally the lowermost sections 12e taper down to the diameter of the bottom cross member 18 which is preferably of a diameter which would enable a person of average height to sit on it with his feet at or near the ground considering a certain amount of compression.

The top cross support member 20 is of extended length protruding beyond the side beams 12 in order to form a substantial bearing member which, when inflated and secured by the anchor tab 22 bears firmly against the fuselage of the aircraft A so as to provide increased stability and insure a straight escape route even in relatively high cross winds. The diameter of the upper cross support member and diameters of the beams connecting their width are relatively small because beam bending moments of the single beam are at a minimum near the beam supports at the aircraft and on the ground and it is desirable to reduce inflation volume requirements when possible.

The actual sliding surface comprise a flexible sheet 24 which is bonded or otherwise secured to the longitudinal beams 12 to extend between them with the beams providing lateral restraining means. However, because the longitudinal beams are designed to yield somewhat under passenger load, there is a tendency for the slide surface to lose some tension in operation, thereby excessively slowing the rate of descent. Therefore, for the purpose of dividing the slide surface into two separate slides, I provide a longitudinal central divider tube 26 which extends substantially the full length of the slide to provide additional tension to the slide surface transversely and, because the divider tube 26 seeks a configuration having a straight axis, it maintains additional longitudinal strength despite bending of the side support beams 14.

The slide is preferably manufactured by forming the longitudinal side beams 12 in the various sections 12a, 12b, etc. and joining them in tandem as above described and in communication with the top and bottom support beams 16 and 18 and the intermediate cross members 20. Then, while the longitudinal beams 12 and cross members are still collapsed, the flexible slide surface 24 is bonded to the longitudinal side beams and the top and bottom cross members 16 and 18. After the slide surface sheet 24 is firmly bonded, the longitudinal members and the cross members are inflated whereby the slide surface sheet is placed under slight tension. While in this state, the central divider tube 26 is bonded to the slide surface while still in collapsed condition (FIG. 3) as by bonding a separate flexible sheet 28 over the divider tube and along both sides to the slide surface. Then, the longitudinal beams may be deflated and the divider tube 26 is brought into communication with one of the other inflatable members as by attaching a hose 30 between the divider tube and one of the transverse members. Subsequently, when the slide tubes 12, 16, 18 and 20 are inflated, the divider tube 26 will be inflated with them to the configuration shown in FIG. 4. When the divider tube is so inflated, the slide sheet 24 is distorted out of its normally planar configuration in order to accommodate the cylindrical configuration of the divider tube 26. Since the hold down sheet 28 is attached to the sheet 24 along lines which are pulled toward each other by the inflated tube 26 the slide sheet 24 is not only divided by the tube 26 to form two slide chutes, but the sheet 24 is tensioned further to form a more effective slide surface.

While this invention has been described in conjunction with preferred embodiments thereof, it is obvious that

modifications and changes therein may be made by those skilled in the art without departing from the spirit and scope of this invention as defined by the claims appended hereto.

5 What is claimed as invention is:

1. The method of manufacturing an inflatable escape slide comprising the steps of:

forming a pair of first flexible tubular members,
forming at least two second flexible tubular members,
securing said tubular members together in fluid-tight communication with the first members displaced longitudinally and spaced to form side rails when inflated and the second members forming transverse supported members,

15 securing a flexible sheet across said longitudinal tubular members,

introducing a pressure fluid to inflate said tubular members,

20 while said tubular members are inflated securing a collapsed, hollow, flexible divider tube to said flexible sheet intermediate said longitudinal tubular members, and

thereafter connecting said divider tube to one of said tubular members for fluid communication therewith.

25 2. The method defined by claim 1 wherein:

said divider tube is secured to said flexible sheet by disposing a second flexible sheet over said divider tube while collapsed and securing it along opposite sides to said flexible sheet.

30 3. The method defined by claim 1 wherein:

each of said first pair of tubular members is formed in at least two sections joined in tandem with the axes thereof when inflated being disposed at a progressively smaller angle from top to bottom with respect to a horizontal plane, and

35 said divider tube is formed with a straight axis, said divider tube being secured to said flexible sheet to extend at least across the junction between said two sections.

40 4. An inflatable escape slide comprising:

a pair of generally parallel side support tubular beams, at least two tubular cross support members communicating with said side support beams,

a flexible sheet secured across said side support beams, and

45 an intermediate divider tube generally parallel to said side support beams and secured to said flexible sheet, said divider tube being secured over a sufficient extent of its periphery in cross-section to distort and apply tension to said flexible sheet when said divider tube is inflated.

50 5. The inflatable escape slide defined by claim 4 wherein:

said tubular beams are formed in at least two sections joined in tandem with the axes of lower sections being disposed when inflated at progressively reduced angles with respect to the horizontal, and

55 said divider tube is formed with a straight axis and is of sufficient length to extend between at least two pairs of sections of said side support beams, said divider tube being in fluid communication with at least one of said support members.
